Primary Examiner — Darlington Ly*Assistant Examiner* — Jessica Lynn Devilbiss(74) Attorney, Agent, or Firm — Vander Velden Law Firm, LLC; Melinda S. Vander Velden(57) CLAIM

The ornamental design for a hinged cover for pickup truck bed, as shown and described.

DESCRIPTION

FIG. 1 is a rear perspective view of the hinged cover for pickup truck bed in an environment of use according to our new design.

FIG. 2 is an enlarged rear perspective view thereof.

FIG. 3 is a front perspective view thereof.

FIG. 4 is a right side view thereof, the left side being a mirror image.

FIG. 5 is a rear side view thereof.

FIG. 6 is a front side view thereof; and,

FIG. 7 is a top view thereof.

Broken lines are used in the drawings to designate environmental structures that form no part of the claim.
